UNITED STATES PATENT OFFICE.

JACOB JACOBS, OF BROOKLYN, NEW YORK.

DESIGN FOR A LENS FOR GRATINGS.

SPECIFICATION forming part of **Design No. 27,493**, dated **August 3, 1897**.

Application filed May 8, 1897. Serial No. 635,753. Term of patent 14 years.

To all whom it may concern:

Be it known that I, JACOB JACOBS, of Brooklyn, in the county of Kings, and in the State of New York, have invented a certain new 5 and original Design for a Lens for Illuminating-Gratings; and I do hereby declare that the following is a full, clear, and exact description thereof, reference being had to the accompanying drawings, in which—

10 Figure 1 is a perspective view of a lens embodying my design. Fig. 2 is a section of the same on the line $x x$ of Fig. 1, and Fig. 3 a section on the line $y y$ of Fig. 1.

15 Letters of like name and kind refer to like parts in each of the figures.

The object of my invention is to provide a design for lenses for illuminating-gratings; and to this end said invention consists in the design for a lens, substantially as hereinafter 20 set forth.

As shown in the drawings, the leading or material feature of my design consists in the

formation on the lens A of numerous projections B and B, each of which has four sides, two of which converge and have the form of quadrangles and the other two have the form of triangles. The projections B and B range in parallel lines, the triangular sides of the projections of adjacent lines being inclined, so that they diverge, the appearance presented 25 being that of V-shaped spaces between the lines of projections.

Having thus described my invention, what I claim is—

The design for a lens, substantially as set 30 forth.

In testimony that I claim the foregoing I have hereunto set my hand this 7th day of May, 1897.

JACOB JACOBS.
